UNITED STATES PATENT OFFICE.

ALBERT M. PIGEON, OF NORRISTOWN, PENNSYLVANIA.

YARN-TENSION DEVICE.

1,385,189.

Specification of Letters Patent. Patented July 19, 1921.

Application filed September 19, 1919. Serial No. 324,888.

To all whom it may concern:

Be it known that I, ALBERT M. PIGEON, a citizen of the United States, residing at Norristown, in the county of Montgomery and State of Pennsylvania, have invented certain new and useful Improvements in Yarn-Tension Devices, whereof the following is a specification, reference being had to the accompanying drawings.

10 The invention relates to yarn tension devices useful in connection with knitting or sewing machinery.

15 The invention relates more particularly to that type of tension devices in which the desired pull upon the yarn is obtained by passing the same between yieldingly opposed tension disks.

20 Heretofore, in the employment of tension devices of the general type above outlined, the arrangement was such that the disks remained perfectly stationary in so far as rotation is concerned, so that wear was necessarily restricted to portions of the disks instead of being evenly distributed over 25 their entire surfaces. Such localized wear eventually resulted in the formation of interfering projections or cutting edges which prevented the proper passage of the yarn, and often caused breakage thereof.

30 In order to overcome these objections, I have devised a simple means whereby the effective contact area between the tension disks and the yarn is not only increased, but the former positively rotated so that 35 wear is evenly distributed, and the passage of the thread greatly facilitated notwithstanding the constant tension thereon.

35 The structure by which these ends are attained will be better understood from the 40 detailed description which follows:

In the drawings, Figure 1 is a front view of a yarn tension device conveniently illustrating my invention, and

Fig. 2, is, for the most part a side elevation of the structure, certain portions being however shown in section to facilitate the understanding of important details.

The device comprises a bracket 1, having near its lower end an integral boss, 2, which is centrally bored to receive the reduced end of a stud, 3. The front face of the boss 2, is slightly recessed as at 4, to form a seat for one end of a bushing 5, preferably of porcelain. This bushing is retained in place through the coöperation of the shoulder 6, of the stud, and the assemblage fixed by

means of a set screw 7, threaded into the boss.

Freely mounted upon the porcelain bushing 5, are a pair of opposed tension disks 8 and 9, which are yieldingly pressed toward each other and against the front face of the boss, 2, by a coiled compression spring 10. Said spring is interposed between a washer 11, bearing directly against the outer tension disk 8, and a thumb nut 12, threaded upon the outer end of the stud 3. By this arrangement, the compressive force exerted upon the tension disks by the spring, may be very minutely adjusted. Associated with the thumb nut 12, is a jam nut 13, through the aid of which the former may be locked against displacement upon the stud 3, after the desired adjustment of the spring is obtained.

75 After passing tangentially between the disks 8 and 9, at one side, (see Fig. 1,) the yarn, indicated in the drawings by the letter Y, is diverted at a point beyond, about a reguide member 15, and re-directed so as to 80 repass between the disks in a like manner at the opposite side. In shape the reguide member 15 closely resembles a spool having a concaved surface, as clearly shown. The center of the curvature, it will be seen from Fig. 2, lies in the plane of the meeting faces 85 of the tension disks 8 and 9, as a consequence of which, the yarn is automatically maintained properly centralized at the point where it is caused to reverse its direction 90 of travel. Member 15, may be either stationary or freely rotatable about an axial stud screw 17, and like the bushing 5, is 95 preferably constructed of a non-corrosive material such as porcelain or the like.

In its passage to and from the disks 8 and 9, the yarn is guided through separate eyelets 18 and 19, set in a lateral extension 20, forming part of the bracket 1. From Fig. 1, it will be observed that these eyelets are so 100 spaced, that by coöperation with the spool element 15, the oppositely moving portions of the yarn are guided in absolute parallelism as they pass between the tension disks.

105 In operation, the yarn Y, fed from a bobbin or other source of supply, (not shown) is passed, in the direction of the arrow in Fig. 1, through the eyelet 17, and thence between the tension disks 8 and 9, at the left 110 side of the illustration. Its circuit is completed by turning about the reguide mem-

ber 16, repassing between the tension disks 8, and 9, upon the opposite or right hand side of the illustration, and finally through the eyelet 19, from whence it may be directed to the machine with which the tension device is adapted to be associated. It is to be especially noted that by this arrangement, the tension disks are positively set into rotation and the attendant slippage 10 between the disks and the yarn in the course of their relative movement, serves to smooth out any inequalities in the latter thereby facilitating its passage and placing the same in a better condition for feeding to the needles of the knitting or sewing machine. Furthermore, in normal operation, the disks are always evenly spaced so that the tension maintained is at all times uniform. In the event of a knot in the yarn, the disks may 20 yield at one side to permit its passage, while the strand at the opposite side is, notwithstanding, fully engaged between the disks so that the necessary working tension is still maintained.

25 Lastly, by reason of the continued rotation of the tension disks, an even distribution of the wear is also effected thereby preventing the formation of any cutting projections or edges which might catch the 30 yarn.

Having thus described my invention, I claim—

1. A yarn tension device comprising a pair of yieldingly opposed tension disks; 35 and means located beyond said disks, where-

by the yarn, after having passed tangentially between the disks at one side, is reversed in the direction of its travel and reguided to repass in a like manner between the disks at the opposite side. 40

2. A yarn tension device comprising a pair of yieldingly opposed, freely rotatable, tension disks; and a spool shaped element located beyond said disks about which the yarn, after having passed tangentially between the disks at one side, is reversed in the direction of its travel and reguided to repass in a like manner between the disks at the opposite side. 45

3. A yarn tension device comprising a 50 pair of yieldingly opposed, freely rotatable, tension disks; a spool shaped element located beyond said disks about which the yarn, after having passed tangentially between the disks at one side, is reversed in the 55 direction of its travel and reguided to repass in a like manner between the disks at the opposite side; and a pair of guide eyelets adapted for coöperation with the spool element in maintaining the oppositely moving portions of the yarn in parallelism as they pass between the tension disks. 60

In testimony whereof, I have hereunto signed my name at Philadelphia, Pennsylvania, this seventeenth day of September, 65 1919.

ALBERT M. PIGEON.
